UNITED STATES PATENT OFFICE.

BIGELOW CROCKER, OF FITCHBURG, MASSACHUSETTS.

APPARATUS FOR WASHING PAPER-MAKING STOCK.

Application filed January 10, 1922. Serial No. 528,250.

To all whom it may concern:

Be it known that I, BIGELOW CROCKER, a citizen of the United States of America, residing at Fitchburg, in the county of Worcester and Commonwealth of Massachusetts, have invented certain new and useful Apparatus for Washing Paper-Making Stock, of which the following is a specification, reference being had therein to the accompanying drawings.

The principal object of my invention may be said to be, first, to wash with rapidity and completeness, and at very small expense, waste-paper fibre, or any paper-making fibre, which has been "cooked" and "defibred"; second, to provide a process, and third, also, apparatus employing it, whereby the above mentioned results may be obtained. Other objects and their attainment will become evident hereinafter.

In so far as the apparatus is concerned, it may be said that the chief characteristics reside 1st, in a stationary wire screen, the inclination, and the size of the meshes, of the screen being such that, by gravity, the paper-making stock moves down over, but not through, the meshes of the screen, while the soiled washing water drains through and away from the meshes of the screen, leaving cleaned fibre stock free of its drained dirty water; and, 2nd, in means for subjecting said cleaned fibre stock to an agitation and disintegration in clean washing water, and draining away, and separating the resulting soiled water from the washed fibre paper stock, as by the above-mentioned screen, having the desired mesh and inclination; while the chief characteristic of the process is that each piece of wet fibre, in its downward movement over the screen, is always subjected to the action of unused clean water which, after contacting the fibre, passes, more or less dirty, through and away from the screen, having completed its usefulness in so far as the washed fibres are concerned.

In the drawings illustrating the principle of my invention and the best mode now known to me of embodying the same in operative structure,

Fig. 1 is a vertical longitudinal section of the apparatus, on line 1—1 Fig. 2.

Fig. 2 is a plan of the apparatus.

Fig. 3 shows an enlargement of the longitudinal section of the first inclined wire-cloth screen and associated apparatus shown in Fig. 1, and a typical washing of paper

fibre passing through this form of my invention.

A mixing box 1, Fig. 1, and settling trough 2, sustained as by hangers 3, comprise a bottom 4, two sides 5, and a closed end 6; a dam 7 separating the box from the trough having across its bottom partitions 8 forming compartments to catch particles of sand, metal and the like. A gate 9 extends across the open end of the settling trough.

Inclined downwardly from the open end of the trough 2, see Fig. 3, is a gravity channel made up of sides 10, and a bottom comprising a series of floors 11, 12, 13 and 14, separated by dependent tanks 15, 16, 17 divided by partitions 18, 19 and 20, Fig. 1, into waste-water basins 21, 22 and 23, and mixing boxes 24, 25 and 26. These basins have outlets 27, 28 and 29, opening into waste-water channels 30, while the floor 14 leads to a return-water tank 31. The mixing boxes are provided with baffles 32, 33 and 34, extending from side to side, and raised from the bottoms of the boxes. Lying above the floors, are inclined at an angle of about 45° sheets of wire-cloth 35, 36, 37 and 38 of about No. 80 mesh wire, resting upon supports 39, 40, 41 and 42, which are fixed to the sides of the gravity channel; the sheets extending as follows: The sheet 35 from the bottom 4 of the settling trough 2, to over the top of the partition 18 of the tank 15; the sheets 36 and 37 respectively, from the tops of the front walls 43 and 44, of the mixing boxes 15 and 16 to the tops of the partitions 19 and 20 of the tanks 16 and 17; and the sheet 38, from the top of front wall 45 of the mixing box 17 to a collecting pipe 46 leading to a stock-chest, not shown.

A stock pipe 47, Fig. 2, and a make-up water-pipe 48 open into the mixing-box 1, the latter pipe being connected with a return water-pipe 49 leading from a rotary pump 50, operated by a suitable driving-pulley 62, and belt 63, to force the water from the return water tank 31 up through the return pipe 49, into the mixing-box 1.

Across and above each sheet of wire-cloth 35, 36, 37 and 38 and mixing-boxes 15, 16 and 17, respectively, are two clean water shower pipes 51, 52; 53, 54; 55, 56; 57 and 58, and a clean water agitating pipe 59, 60 and 61 having, respectively, valves 80, 81, 82, 83, 84, 85, 86, and 87, and 88, 89, and 90, and each of these pipes having a series of small apertures whereby showers of clean water

can be cast against their respective wire sheets and into the mixing-boxes.

I will now describe the operation of my invention.

- 5 Paper-stock, mixed with water, and previously saponified and "defibred" by any of the well known processes in paper-making, is introduced through the stock pipe 47, Figs. 1 and 2, into the mixing box 1 10 which is supplied with an abundance of water through the make-up water pipe 48; the resultant fluid being a very thin and milky mixture containing a very small percentage of fibre say, 3%. From the mixing-box, it flows over the dam 7, into the settling trough 2, where particles of metal, sand and the like are collected in the compartments formed by the partitions 8. 15 The liquid paper-stock mixture 64, Fig. 20 3, next leaves the settling trough 2 by passing under the small gate 9, and, flowing in a thin liquid sheet 65; onto the sheet of wire-cloth 35. Because of the fineness of the mesh, some of the dirty water 66 percolates through, and either drops directly into the waste channel 11, or flows along the under side of the wire-cloth, meets and runs down the support 39, and falls into the waste channel also; further, some of the 25 water remaining upon the top surface of the wire screen, passes through the mesh above the support, being greatly aided by the capillary attraction due to the proximity of the support. This gradual removal of 30 water from the mixture in its downward course, leaves small masses of wet fibre 67 moving downward over the wire cloth because of either their own weight or the moving water still on top of the 35 cloth. But in this downward movement, these small masses of fibre partially drained of dirty water, pass under a clean water shower 68 comprising jets of water from the shower pipe 51, branching from the 40 main fresh water shower supply pipe 69; these jets being cast at the top face of the inclined wire trough, at an angle say, less than a right angle. By reason of this shower, the small masses of fibre are 45 disintegrated, dashed with clean water and thereby washed of their saponified particles of dirt, ink and color; much of the resulting dirty water 70 being driven by the shower, through the wire mesh into the 50 waste channel.

The fibres after passing the first shower 68, begin again to move downward along the wire cloth, and lose their water as already described, and encounter a second 60 clean water shower 71, like the first, with the result that the fibres are again disintegrated and scoured with clean water, while most of the dirty water is driven by the shower through the wire mesh into the waste water channel; the washed fibre

72 still again sliding and rolling downward along the wire-cloth, and losing its water through the above-mentioned percolation and capillary attraction until it drops into the second mixing box 24, which receives 70 jets 73 of clean water from the agitating pipe 59, also branching from the main clear water supply pipe 69. Here the fibres are again thoroughly mixed with clean water, as by natural agitation, and, 75 passing under the partition 32, upon leaving this second mixing box, drop over and down onto the second wire cloth 36, and are drained of most of the water, subjected to the action of separate streams of jets of clean water, most of which drive through the screen between the supports, and pass off and into the dirty water escape. Obviously, while on the second screen, as on the 80 first, the masses of fibre are drained, then disintegrated and washed; then again drained, disintegrated and washed, and finally drained; to be again drained and washed if necessary, by repeating the above described operation over the third, and, perhaps, over the fourth wire screen such as described. From the last screen used, say the fourth, 14, the small masses of drained 85 washed paper fibre, drop into the collecting pipe 46, from which the washed paper stock 90 flows through the delivery pipe to the stock-chest.

It is to be noted that the water escaping from the first screen 35 is dirty; that from the second 36, less dirty; that from the 100 third 37 quite clean; while that from the fourth is for all practical purposes, clean, and is again serviceable for further use in this process; in which event, it can be caught in the waste return water tank 31, and by the pump 50, returned through the return water pipe 49, to the make-up water pipe 48, and emptied again into the first mixing box 1 used in the operation of this apparatus.

It is also found, that in order to have the used water from the escape channels flow away through the waste pipe, an air vent 74 must be provided in each escape 110 channel.

Still further, if thought desirable, mechanical agitation in the mixing box 25, may be accomplished, as by a paddle 75 rotated as by a belt 76 driven from the countershaft 77, operating the return water 120 pump.

To state more particularly as to the necessary inclination, and the requisite size of mesh to be given to the screen, it must be remembered that if a wire screen is to be 125 used, to accomplish the object of my invention the dirty water must pass through it, and all of the fibre must roll or slide down over it, by reason of gravity. If the inclination is too much, the water, or a large 130

portion of it, will flow down over the top of the screen, and will not drain away from the fibre. If the inclination is not enough, the fibres will not slide or roll down over the top surface of the screen, but will settle into the small mesh, and fill them up and prevent the dirty water from draining away through the mesh. Experimentation has shown that when the inclination of the screen is about 45°, and the wire used is about a No. 80 mesh wire, the dirty water will pass through, and all of the fibre will roll or slide down over the top surface of the screen; and it was also noticed that on such a screen in use, any short fibres of the stock that might become caught in the mesh, are at once seized and pulled out therefrom, by the long fibres of the down-coming masses of wet fibre passing over them. In this way, the meshes of the screen are kept free from clogging fibres, for long periods of time.

It is evident that, broadly, my invention is not susceptible of definition in terms of meshes to the inch, and of angles of inclination, of the screen, and that practical workers in the art will have no difficulty in understanding that the inclination and the mesh of the screen must be so correlated, that gravity will separate the dirty water from the kind of paper making stock to be washed.

It has been found that frequently a satisfactory washing may be obtained without the additional washings brought about by the use of clean water sprays, as 51, and/or 52, controlled by valves 80 and/or 81; but in any event, the person using my invention has at his disposal apparatus whereby he can wash his paper stock with or without any one or more of these clean water sprays, as occasion demands.

From the foregoing, it will be evident that the process is continuous, rapid, complete, and cheap to carry out; that gravity and water do all the work and that the only attention required is that of an operator controlling the proper supply of paper stock solution, and of clean water from the fresh water pipe.

The value of my invention becomes particularly obvious when compared with any mechanical process of washing paper stock.

Desiring to protect my invention in the broadest manner legally possible,

What I claim is:—

1. Apparatus for washing paper making fibre stock, consisting of an inclined wire screen, the size of its mesh and the angle of its inclination permitting dirty water 60 after the delivery of the stock suspended in water, to the screen to pass through and away from the screen, and only the stock to remain upon and move down over the screen, by gravity. 65

2. Apparatus for washing paper making stock, consisting of an inclined wire screen the size of its mesh and the angle of its inclination permitting the dirty water, after the delivery of said stock, suspended in 70 water, to the screen, to pass through and away from the screen, and only the stock to remain upon and move down over the screen, by gravity; a mixing box for said stock at the bottom of the said screen; means 75 for mixing said drained stock with clean water in said box; and a second inclined screen like said first mentioned screen, for separating, by gravity, the washed stock from its dirty water. 80

3. Apparatus for washing paper making stock, consisting of an inclined wire screen the size of its mesh and the angle of its inclination, permitting the dirty water, after the delivery of said stock, suspended in 85 water, to the screen, to pass through and away from the screen, and only the stock to remain upon and move down and over the screen, by gravity; means whereby a suitable stream of clean water may be cast against 90 the wet stock being drained and moving down over the screen to disintegrate, wash and rinse said stock, and pass through and away from said screen; a mixing box to receive said stock at the bottom of said 95 screen; means for mixing said drained stock with clean water, in said box; a second inclined wire screen like said first mentioned screen, for separating, by gravity, the washed stock from its dirty water; and 100 means whereby a suitable stream of clean water may be cast against the wet stock being drained and moving down over said second screen, to disintegrate, wash and rinse said stock, and pass through and away 105 from said screen.

In testimony whereof I hereunto affix my signature.

BIGELOW CROCKER.
